YARN CARRIER

Edward Jentsch, Clifton, N. J.

Application November 4, 1948, Serial No. 58,265

3 Claims. (Cl. 66—126)

1

The present invention relates to improvements in yarn carriers and accessories. It relates more particularly to a yarn carrier having a removable thread-guide tube and a carrier-tube releaser by means of which the thread-guide may be easily removed from the carrier and replaced upon becoming worn or otherwise damaged.

The present invention provides means for accurately positioning the thread-guide tube without interference with the threading of the carrier and also prevents damage or injury to the carrier during the removal or installation of the thread-guide tube. The various objects and advantages of the invention will be best understood from the following description and the accompanying drawings in which:

Fig. 1 is a perspective view of a portion of a yarn carrier embodying the invention;

Fig. 2 is a front view of the carrier jaws and the thread-guide tube as illustrated in Fig. 1;

Fig. 3 is a section view taken along the line 3—3 of Fig. 2, but on a somewhat enlarged scale;

Fig. 4 is a section view taken along the line 4—4 of Fig. 1; but on an enlarged scale;

Fig. 5 is a section view taken along the line 5—5 of Fig. 1;

Fig. 6 is a fragmentary view in perspective of a yarn carrier and a carrier-tube releaser;

Fig. 7 is a top view of the carrier-tube releaser as illustrated in Fig. 6; and

Fig. 8 is a plan view of the carrier-tube releaser as illustrated in Fig. 6.

Referring now to the drawings in detail there is a yarn carrier, designated generally by the numeral 1 that is of the type suitable for use in full fashioned hosiery machines. However, it will be understood that the present invention is not to be limited to a particular type of yarn carrier, but may be used in conjunction with any suitable type of carrier; as for example, a yarn carrier of the type illustrated and described in my copending application Serial No. 58,266 filed November 4, 1948, now Patent No. 2,560,955.

The yarn carrier 1 consists of a downwardly sloping body 2 with a pair of opposed spring-jaws 3 and 4 that extend downwardly at an angle to the carrier body 2 at the lower end thereof. The jaws 3 and 4 are shaped to engage with and hold a thread-guide tube 5 in proper position at the lower end of the yarn carrier 1 for guiding a yarn or thread to a knitting machine.

The spring-jaws 3 and 4 have recessed portions in their faces, as indicated at 6 and 7 in Fig. 2, that are located beneath an enlarged opening 28 between the spring-jaws. The recessed portions 6 and 7 expose the front and top of the guide

2

tube 5 when it is positioned between the jaws 3 and 4 so that the top of the tube 5 is fully accessible to the operator. This permits the operator to thread the yarn through the tube 5 with little difficulty. Projections 8 and 9 extend forwardly from the tops of the recessed portions 6 and 7 of the jaws, respectively, and engage with the top of the thread-guide tube 5 at the rear edge thereof when the thread-guide tube is inserted between the jaws. The engagement of the thread-guide tube 5 with the projections 8 and 9 positions the lower end of the thread-guide tube in the yarn carrier so that it will be accurately located with respect to the knitting machine.

10 The projections 8 and 9 may be spaced apart by a distance at least equal to the inner diameter and not greater than the outer diameter of the yarn guide tube 5 so that when the jaws 3 and 4 engage with the thread-guide tube 5, the projections 20 will not extend beyond the inner edges of the thread-guide tube 5 or interfere with the passage of yarn through the tube.

The spring-jaws 3 and 4 of the carrier are also provided with apertures 10 and 11 into which the 25 prongs 12 and 13 of a carrier tube releaser, designated generally by the numeral 14, may be inserted. The body of the carrier tube releaser 14 is a bifurcated member having legs 15 and 16 from the ends of which the prongs 12 and 13 that are shaped to engage the spring-jaws extend. A 30 threaded member 17 is threaded through the rear of the bifurcated body of the carrier tube releaser 14 and extends between the legs 15 and 16. The end of the threaded member 17 is tapered and may be brought into and out of engagement with tapered seats 18 in opposed surfaces of the legs 15 and 16 by turning the threaded member 17 in an appropriate direction. Thus, when the threaded member 17 is screwed 35 into the carrier tube releaser 14, the legs 15 and 16 and the prongs 12 and 13 will be uniformly spread apart and when it is screwed out the legs 15 and 16 will return to their normal position.

The end of the threaded member 17 extending beyond the body of the carrier tube releaser 14 45 may be provided with a knob 19 by which it may be screwed into or out of the body of the carrier tube releaser 14 and the threaded member 17 also carries a stop in the form of an adjustable collar 20 that is located on the threaded member 50 between the knob 19 and the back of the body of the carrier tube releaser 14. The collar 20 is provided with a set screw 21 by means of which its position on the threaded member 17 at a desired location may be fixed. When the threaded member 17 is screwed into the body of the carrier

tube releaser 14, the collar 20 engages with the rear of the body of the carrier tube releaser 14 and limits further movement of the threaded member 17 and thus, limits the distance the legs 15 and 16 and the prongs 12 and 13 will be spread to that required to release the thread-guide tube 5 from the carrier jaws 3 and 4.

The carrier tube releaser 14 spreads the carrier jaws 3 and 4 apart uniformly by the force exerted through the prongs 12 and 13 and the limited movement of the prongs 12 and 13 prevents the carrier from being damaged by over-expansion of the jaws 3 and 4. When the carrier tube releaser 14 has been inserted and the jaws 3 and 4 have been expanded sufficiently to release the thread-guide tube 5, the carrier tube releaser 14 will hold the jaws 3 and 4 in expanded condition as long as desired. This leaves both hands of the operator free to remove the thread-guide tube 5 and insert a new thread-guide tube in the carrier.

The reverse side of body 2 of the yarn carrier may be provided with wear resisting guides 22 over which the yarn passes. The wear resistant guides 22 may be in the form of clips of hardened steel wire that have prongs 23. The prongs 23 fit into openings 24 in the carrier body 2 and engage with the carrier body 2 to hold the guides 22 in place. However, the guides 22 may be easily removed and replaced when desired. Other types of replaceable guides that might be used in various types of carriers in place of the guides 22 are shown and described more fully in my copending application Serial No. 58,267 filed November 4, 1948. The guides 22 may also be secured to the carrier body 2 by soldering, brazing or the like or they may be formed by forcing out sections of the carrier body 2 if it is not desired to have them replaceable. The carrier body 2 and the guides 22 are provided with grooves 24' and 23', respectively, to direct the thread as it passes down the carrier.

After the thread passes over the guides 22, it passes through an opening 25 in the carrier body 2 and then is guided down the front of the carrier over a groove 26 by a tongue 27 across the enlarged opening 28 to the thread-guide tube 5. If desired the groove 26 may be provided with wear resisting guides 22 such as previously described. The tongue 27 may be beveled or tapered on its front and rear, as shown in Fig. 5, to prevent interference with or damage to adjacent carriers in a multi-carrier machine.

It will be understood that various modifications and changes in the embodiment of the invention as illustrated and described herein may be made by those skilled in the art without departing from the scope of the invention as defined by the following claims.

I claim:

1. A yarn carrier of the type wherein a pair of spring jaws located at the delivery end of the carrier engage with and hold a thread-guide tube

in a slotted opening between said jaws with the top end of said tube communicating with an enlarged opening in the carrier above the tube gripping portions of said jaws which is characterized by said jaws having recesses in the outer faces thereof, said recesses being located at the top of the slotted opening between the jaws and exposing the front and top end of the thread-guide tube.

2. A yarn carrier of the type wherein a pair of spring jaws located at the delivery end of the carrier engage with and hold a thread-guide tube in a slotted opening between said jaws with the top end of said tube communicating with an enlarged opening in the carrier above the tube gripping portions of said jaws which is characterized by said jaws having recesses in the outer faces thereof, said recesses being located at the top of the slotted opening between the jaws and exposing the front and top end of the thread-guide tube and a projection carried by at least one of said jaws and extending into the recess therein at the top of the slotted opening between the jaws, said projection engaging with the top of the thread-guide tube at the rear thereof and positioning the thread-guide tube in the slotted opening between the jaws.

3. A yarn carrier of the type wherein a pair of spring jaws located at the delivery end of the carrier engage with and hold a thread-guide tube in a slotted opening between said jaws with the top end of said tube communicating with an enlarged opening in the carrier above the tube gripping portions of said jaws which is characterized by said jaws having recesses in the outer faces thereof, said recesses being located at the top of the slotted opening between the jaws and exposing the front and top end of the thread-guide tube, a projection carried by at least one of said jaws and extending into the recess therein at the top of the slotted opening between the jaws, said projection engaging with the top of the thread-guide tube at the rear thereof and positioning the thread-guide tube in the slotted opening between the jaws and each of said spring jaws having a circular opening therein located intermediate its length for reception of the prongs of a jaw-spreading tool therein to release the jaws from engagement with the thread-guide tube.
